UNITED STATES PATENT OFFICE.

JAMES H. SPRAGUE, OF NORWALK, OHIO.

DESIGN FOR A KITE-COVER.

SPECIFICATION forming part of Design No. 16,895, dated September 7, 1886.

Application filed April 2, 1886. Serial No. 197,540. Term of patent 7 years.

To all whom it may concern:

Be it known that I, JAMES H. SPRAGUE, a citizen of the United States, residing at Norwalk, in the county of Huron and State of Ohio, have invented a new and original Design for Kite-Covers, of which the following is a specification, reference being had to the accompanying drawing, forming a part thereof, and in which the figure represents a plan 10 view of my newly-designed kite-cover.

The leading feature of my invention consists in a cover for kites having a central ornamentation and a series of hexagonal figures or spaces around the cover and the central ornamentation, and inclosing the latter.

My design further consists in a central ornamentation in which one or more persons are represented flying kites, and in a series of hexagonal figures that form spaces around 20 the cover, and surrounding or inclosing the above-described central ornamentation.

A designates the cover of the kite, which is substantially rectangular in form, and incloses a continuous border-line, A', that consists of 25 a short horizontal border-line, a, at the upper edge of the cover, and the inclined lines a', that diverge in opposite directions from each other and from the ends of the line a, and at its lower edge the border A' has a horizontal line, a', that is parallel with the line a, and by the inclined lines a', that connect with the extremities of the lines a' a'. Each of said border-lines a a' a' has two or more lines, a', disposed parallel therewith, and of the 30 same or different colors.

B is the central ornamentation in the middle portion of the kite-cover, and inclosed within a space that is approximately the same shape as the kite-cover, but of smaller dimensions.

40 This ornamentation is inclosed by border-lines B', which comprises the lines b, which are parallel with but a short distance from the lines a' of the border-line A', and by the lines b', which are likewise parallel with the lines 45 a', and at a distance therefrom equal to the distance between the lines a' b', thus providing a space intermediate of the border-lines A' B' of the kite-cover and of the ornamentation in the middle thereof. In this central 50 pictorial ornamentation a rural or other scene is represented, in which the trees of the woods are disposed on opposite sides of a clear space,

and a lake or body of water, on which is a boat sailing, is seen, and also the mountains and sky in the distance. A man is represented sitting on a log or stump of a tree and in the act of shouting, with his hands raised. A woman and one child are flying kites, and a dog is also represented running away from the group of people, and having a kite-string 55 tied to his neck or to a stick in his mouth, and with another child running after it. At the head of the central ornamentation is represented a star-shaped figure, C, which has scrolls or curved lines formed about it, and 60 immediately below the extreme upper edge of the kite-cover and above the figure C is represented a Maltese cross, D. At the bottom of the central ornamentation, B, is a scroll or banner having a rod passed through the upper edge thereof, and with spear-shaped ends, and having a clear open space at its middle 65 surrounding the scroll. E is a series of small plants whose leaves and branches partially overlap or extend over the scroll. 70

At the lower edge of the cover A, within the border-line a', and at the middle thereof, is an upwardly-carved line, F, having a serrated or scalloped edge projecting toward the scroll, and to each side of the scalloped or serrated 75 edge figure F, and at the lower corners of the scroll E, are cornucopias or "horns of plenty," as at G. The enlarged ends of these figures G are nearest to the scalloped or serrated edge figure F, and they have similar serrations or scallops, f, around the said enlarged ends, and the contracted end of each of these cornucopias is curved upon itself, and has a star, g, at its extreme end, the said stars of the cornucopia lying at the extreme lower- 80 most corners of the kite-cover.

Between the border-lines of the kite-cover and the central ornamentation thereof is a series of figures, H, which are hexagonal in form. Two of the boundary-lines of the hexagonal 85 figures lie parallel with the boundary-lines A' B' of the kite-cover and the central ornamentation, B, theron, and the remaining boundary-lines of each of said figures meet at the middle of the space inclosed by the lines A' 90 B' of the cover and ornamentation B, and at an angle.

Between the angles or corners of two adjacent hexagonal figures, H, at the base of the

kite-cover, is another figure, I, that lies in the middle of the space between the boundary-lines A' B'. This figure comprises a small inner circle, a larger outer circle concentric therewith and inclosing the same, a series of ellipses radiating from the smaller circle and equidistant apart, and a dot intermediate of two adjacent ellipses, the larger or outer circle having a scalloped or serrated edge. At the angle where the lines b b' join, the figure I is in rear of the corners or angles of the two adjacent hexagons II, and a stem, I', is projected from the figure I to the angle where the said lines b b' meet, and this stem has the leaves and flowers, as shown.

Between the hexagonal figures at the upper portion of the cover and the lines a a' is a star, J, which is partially concealed by said figures, and has a circular center which connects the angles or corners of the hexagons.

Above the hexagons II, at the upper end of the cover, and on each side of the Maltese cross D, is arranged a star, K.

The upper portion of the cover has triangular flaps L connected thereto, and separated from the border-lines a' thereof by a broad line, l, that extends around the side edges of the said flap.

In the middle of the space inclosed by the border-line l is arranged a hexagon, L', and at the corners of the said space are triangular figures M.

At the lower side of the kite-cover, and adjoining the lines a' thereof, are the lower flaps, N, which are also triangular in shape, and each has a boundary-line, m, around its edges, the boundary-lines l m of the flaps L N joining each other, as clearly shown.

Within the space inclosed by the boundary-line m each flap has a figure, O, which is enlarged at the lower end and provided with a ball and tapered toward the upper end of the cover, the tapering portion having lateral arms intermediate of its length and an arrow-headed point.

It will be observed that I provide a very pretty design for a kite-cover, which presents

to the eye a central ornamentation representing several persons flying kites, and a series of hexagonal figures around the cover and the 50 said ornamentation.

Each of the flaps is provided with parallel lines o, that lie a short distance apart, and at each corner of the kite proper within the border-lines of the cover is provided a dot or circle, p.

I claim--

1. The design for a kite cover herein shown and described, the same consisting of a central ornamentation, B, of persons flying kites, 60 and a rural scene, border-lines A' B' around the cover, and the ornamentation thereon, a series of figures, II, intermediate of the border-lines A' B', and a scroll or banner, E, at the base of the ornamentation.

2. The design for a kite-cover herein shown and described, the same consisting of a central ornamentation, B, a series of hexagonal figures around the ornamentation, a scroll or banner at the base of the picture, the horns of 70 plenty or cornucopias at each side of the scroll or banner, and the plants having their branches surrounding the scroll and cornucopias.

3. The design for a kite-cover herein shown and described, the same consisting of a central 75 pictorial ornamentation of persons flying kites and a series of open figures or spaces around the said ornamentation.

4. In a design for kite-covers, a central ornamentation and a series of hexagonal figures 80 or spaces around the edge of the cover and the ornamentation, and inclosing the latter.

5. In a design for kite-covers, a central ornamentation, a series of hexagonal figures surrounding the ornamentation, and the rosettes 85 intermediate of the figures.

In testimony that I claim the foregoing as my own I have hereto affixed my signature in presence of two witnesses.

JAMES H. SPRAGUE.
